UNITED STATES PATENT OFFICE.

LOUIS BORGENICHT, OF NEW YORK, N. Y.

DRESS.

1,331,799.

Specification of Letters Patent. Patented Feb. 24, 1920.

Application filed March 24, 1919. Serial No. 284,572.

To all whom it may concern:

Be it known that I, LOUIS BORGENICHT, a citizen of the United States, and a resident of the city of New York, county of Kings, 5 and State of New York, have invented certain new and useful Improvements in Dresses, of which the following is a specification.

The invention relates to a child's dress of 10 the type in which a re-arrangement of parts will permit the garment to be worn in two different styles.

The primary object of the invention is to provide a simple form of child's dress, in 15 which a blouse element independent of the skirt is designed when falling loose to provide a middy suit effect and which, when the lower portion is fastened up, will form a puffed blouse or Russian sailor effect.

Another object of the invention, incidental 20 to the primary object, is to provide fastening means for holding the blouse in its puffed position and which can be utilized to produce an ornamental effect when not utilized 25 as a fastening means.

Another object of the invention is to provide in a simple construction, a support for the skirt element which will maintain the skirt in fixed position relative to the wearer's 30 shoulders and independent of any adjustment of the blouse element.

Various other objects and advantages of the invention will be in part obvious from an inspection of the accompanying drawings 35 and in part will be more fully set forth in the following particular description of one form of device embodying my invention, and the invention also consists in certain new and novel features of construction and combination of parts hereinafter set forth and 40 claimed.

In the accompanying drawings:

Figure 1 shows a view in front elevation of a preferred form of the invention with 45 the blouse arranged to produce a middy-suit effect;

Fig. 2 is a view similar to Fig. 1 with the blouse looped up to form the Russian sailor effect;

50 Figs. 3 and 4 are transverse sectional views taken respectively upon the line 3—3 of Fig. 1 and 4—4 of Fig. 2; and

Fig. 5 is an enlarged sectional view of the 55 fastening means shown at the front of the waist-line in Fig. 4.

In the following description and in the claim, parts will be identified by specific names for convenience of expression but they are intended to be as generic in their application to similar parts as the art will 60 permit.

The dress comprises an undergarment 10 and a blouse 11, both supported from the shoulders of the wearer and independent of each other. The undergarment comprises an 65 underwaist 12 and a skirt 13 fastened thereto at the waist-line 14 by any suitable means such as the stitching 15. It is of course obvious that the skirt and underwaist may be otherwise fastened together or may even be 70 made in one-piece, the essential point being that the skirt should have a definite position with reference to the shoulders of the wearer and in this way be not effected by changes in the arrangement of the blouse. 75

The undergarment is provided with a series of button-holes 16 at the waist-line and which in the illustrated embodiment of the invention extends through the overlapped portion of the underwaist and skirt. The 80 blouse has a length so that when falling loose, as shown in Figs. 1 and 3, the lower edge 17 extends below the waist-line so as to give the middy-suit effect. The lower edge 85 of the blouse is turned up to form a cuff 18 thus improving the effect of the blouse but it is obvious that this cuff is no material part of the invention. The cuff is provided with a series of buttons 19 which when in the position shown in Fig. 1 coacts with the 90 cuff to provide a pleasing, decorative effect to the lower portion of the blouse. When the blouse is looped under and upwardly as shown in Figs. 2 and 4, the buttons 19 are caused to engage the button-holes 16 as 95 shown more particularly in Fig. 4. There is thus produced the puffed blouse or Russian sailor effect.

By means of a device of this character, 100 two different appearances can be made with the same garment and in either position, the re-arrangement of the lower portion of the blouse will have no effect upon the position of the skirt.

While I have shown and described, and 105 have pointed out in the annexed claim, certain novel features of my invention, it will be understood that various omissions, substitutions and changes in the form and details of the device illustrated and in its 110

operation may be made by those skilled in the art without departing from the spirit of the invention.

Having thus described my invention, I claim:

In a child's dress, the combination of a complete unit formed of an underwaist supported from the shoulders and a skirt hung therefrom at the waist line whereby the unit is supported solely from the shoulders of the wearer, said unit provided with a series of circumferentially spaced apart button holes at the waist line, of a separate blouse worn over the unit and otherwise independent thereof, said blouse having a length when falling free to extend below the waist-line

and having a loose, lower edge extending continuously about the skirt and turned back upon itself, thereby to form a middy-suit effect on all sides and buttons secured to the outside of the blouse below the waist-line whereby when the lower continuous edge of the blouse is turned under, and the buttons on the blouse engaged in the coacting button-holes in the unit, the free edge is supported by the unit and a puffed blouse suit or Russian sailor effect is produced.

Signed at New York city, in the county of New York and State of New York, this 19th day of March, A. D. 1919.

LOUIS BORGENICHT.
